United States Patent [19]

Imamura et al.

[11] Patent Number: Des. 315,722

[45] Date of Patent: ** Mar. 26, 1991

[54] CENTRAL PROCESSING UNIT FOR COMPUTER

[75] Inventors: Tetsuya Imamura; Hirokatsu Funaki, both of Osaka; Natsu Use, Hyogo, all of Japan

[73] Assignee: Matsushita Electric Industrial Co., Ltd., Osaka, Japan

[**] Term: 14 Years

[21] Appl. No.: 360,166

[22] Filed: May 31, 1989

[30] Foreign Application Priority Data

Feb. 2, 1989 [JP] Japan 1-3612

[52] U.S. Cl. D14/100
